UNITED STATES PATENT OFFICE.

ARTHUR WHITE, OF SHEBOYGAN FALLS, WISCONSIN.

GAS GENERATOR AND BURNER.

Application filed February 23, 1923. Serial No. 620,724.

This invention relates to improvements in gas generator and burner, more particularly, although not solely, adapted for household use.

It is one of the objects of the present invention to provide a gas generator and burner having novel means for generating the gas and for mixing the gas with air to form a more perfect combustible fluid.

A further object of the invention is to provide a gas generator and burner having supplemental means for supplying air to the vaporized fluid while burning.

A further object of the invention is to provide a gas generator and burner in which the major portion of the burner is molded from soapstone or other like material reinforced with metal covering portions.

A further object of the invention is to provide a gas generator and burner which may be easily installed in the ordinary stove and used in connection therewith.

A further object of the invention is to provide a gas generator and burner having means for regulating the amount of air supplied to the burner.

A further object of the invention is to provide a gas generator and burner having conduction plates for conducting the heat from the incoming gas outwardly to the cooler metal burner holder.

A further object of the invention is to provide a gas generator having valves actuating synchronously for regulating the proportional volume of the primary gas and air to insure more intense heat in burning.

A further object of the invention is to provide gas generators and burners for cook stoves having means for adjusting same to positions farther apart or close together so as to bring them directly under the stove plates of different sized stoves.

A further object of the invention is to provide a gas generator and burner which is of simple construction, is efficient in operation, and is well adapted for the purpose described.

With the above and other objects in view, the invention consists of the improved gas generator and burner and its parts and combinations as set forth in the claims, and all equivalents thereof.

In the accompanying drawings, in which the same reference characters indicate the same parts in all of the views:

Fig. 1 is a top view of the improved gas generator and burners, one portion of one of the burners being removed to show the construction therebeneath;

Fig. 2 is a side view thereof, parts being shown in section;

Fig. 3 is a top view of one of the conduction plates;

Fig. 4 is a transverse sectional view thereof, taken on line 4—4 of Fig. 3;

Fig. 5 is a transverse sectional detail view of one of the burners;

Fig. 6 is a detail sectional view taken at right angles to that shown in Fig. 5;

Fig. 7 is a horizontal sectional detail view taken on line 7—7 of Fig. 5;

Fig. 8 is a detail view of one of the valves;

Fig. 9 is a detail view of the primary air control means; and

Fig. 10 is an end view thereof including the means for moving the valve.

Referring to the drawings, the numeral 12 indicates a supporting member of rectangular form which is of open construction and is provided with aligned elongated slots or openings 13 to adjustably receive

the downwardly extending lugs 14 of the burner holding members 15 and are clamped thereto by screws 14'.

The burners 16 positioned above the holding members 15 are connected thereto by screws 17 and 17'.

Each burner comprises the supply member 18, the standard 19, the burner member 20, the lower burner casing 21 and the burner upper casing or cover 22.

The standard 19 is preferably formed of soapstone or other like material and is provided with a central vertically extending bore 23 of Venturi shape into which extends the gas nozzle 24 forming part of the supply member 18.

The upper end portion of the Venturi shaped bore is closed by a plug 25 forming part of the standard 19, which is also formed of soapstone or like material.

When molded of soapstone or like material, more efficient radiation is provided, and the burner openings are less liable to carbonize and fill up and the parts may more easily be made.

The nozzle 24 is spaced a slight distance from the wall forming the Venturi bore to permit the entrance of air thereto through the air openings 25' extending through the supply member 18.

A perforated valve plate 26 pivotally mounted on the underside of the supply member 18 controls the supply

of air to the Venturi bore. Said air valve is formed with an outwardly projecting bifurcated arm 26' for receiving the depending pin 27 of the control bar 28 which also 5 controls the supply of gas to the Venturi bore through the valve 29 which is positioned in the supply member 18.

The upper portion of the standard 19 is provided with radial ports 30 which extend 10 from the Venturi bore to the mixing chamber 31 formed by the lower casing 21 and adjacent parts. A mixing screen 32 positioned in the upper portion of the Venturi bore and covering the openings 30 thoroughly 15 mixes the vapor and air passing therethrough. Annular conduction plates 33 positioned in the upper portion of the chamber 31 are provided with elongated perforations 33' which are radially offset with 20 relation to each other and through which the mixed vapor passes upwardly from the mixing chamber 31. The burner member 20 is formed with annularly positioned upwardly extending truncated projections 34 25 having openings 34' extending vertically therethrough which communicate with the chamber 31 above the conduction plates 33. The upper casing or cover 22 is positioned above the burner 20 to form an air space 35 and the casing is formed with upwardly 30 extending perforated tubular portions 22' which surround the truncated projections 34 and permit the passage of air therearound.

The standard 19 is provided with a plurality of vertically extending air ports 36 which open outwardly at their lower ends, and at their upper ends communicate with the air space 35 to furnish hot air around each individual burner and increase the efficiency 40 thereof.

A vapor generator in the form of two convolutions of a pipe 37, is positioned above the burner casing 22 and its opposite ends are connected to vertical pipes 38 and 45 39 extending upwardly alongside of the burner. The pipe 38 is the fuel supply pipe and leads from a source of supply, while the pipe 39 connects with the valve 29 leading to the burner 20 so that oil or other 50 fluid flowing upwardly through the pipe 38 and through the generator 37 will be heated and vaporized and flow downwardly through the pipe 39 to the burner in the form of a gas and be mixed with the air before 55 burning. A needle valve 38' controls the fluid supply. The control bar 28 is connected to both gas valve 29 and the air valve 26 so that as the supply of gas is increased the supply of air will also be increased. A link 40 pivotally connected to 60 one end portion of the bar 28 and the holding member 15 provides for said bar being easily reciprocated to adjust the valves.

The outer and inner ring of tubular perforated portions 22' of the cover casing

are joined together by upwardly extending flanges 41 to form a receptacle like space for holding liquid fuel which may be burned preliminarily to heat the generator in starting the burner.

To start the gas generator and burner in operation, a small quantity of oil or alcohol, preferably alcohol, is put into the grooves of the lower supporting plate and ignited. The combustion incidental thereto warms up 70 the whole burner. Another small quantity of alcohol is also put into the depressions in the cover and the same ignited, which results in heating the generating coil to the proper temperature for converting the liquid fuel into gas, after which the fuel supply valve is opened slightly, the fuel being sprayed into one end of the generating coil, is promptly gasified, and passing through the coil goes to the gas supply valve which is then opened, the gas going through the nozzle into the Venturi bore and mixing with the air from the regulating air valve on its way up through the mixing screen and radial ports to the mixing chamber, then through openings in the conduction plates and through the burner openings where it is ignited by the flames of the mainie.

From the foregoing description, it will be seen that the gas generator and burner is of very simple construction and may be easily installed in an ordinary stove, and is well adapted for the purpose described.

What I claim as my invention is:

1. A gas generator and burner, comprising a support, a supply member connected thereto and having an upstanding nozzle, a standard connected to the supply member and having a bore entered by the nozzle, a burner member carried by the standard and having upwardly extending tubular burner projections and a burner opening, an upper casing positioned above the burner member and having spaced openings into which the projections extend, a casing engaging the standard and the burner for directing vapor from the standard to the burner opening, and a generator member positioned above the burner and connected to the fuel supply member and having means for connection with a source of fuel supply.

2. A gas generator and burner, comprising a support, a supply member connected thereto and having an upstanding nozzle and a valve controlling the fuel supply thereto, a standard connected to the supply member and having a bore entered by the nozzle and also having an air inlet opening, a burner member carried by the standard and having upwardly extending tubular projections of tapering form and burner openings and an opening in communication with the air inlet opening, an upper casing positioned above the burner member and having spaced open-

ings into which the projections extend, a casing engaging the standard and the burner for directing vapor from the standard to the burner opening, and a generator member positioned above the burner and connected to the valve and having means for connection with a source of fuel supply.

3. A gas generator and burner, comprising a support, a supply member connected thereto and having an upstanding nozzle and a valve controlling the fuel supply thereto, a standard connected to the supply member and having a bore entered by the nozzle and also having an air inlet opening, a burner member carried by the standard and having upwardly extending tubular projections of tapering form and burner openings and an opening in communication with the air inlet opening, an upper casing positioned above the burner member and having spaced openings into which the projections extend, a casing engaging the standard and the burner for directing vapor from the standard to the burner openings, a conduction member positioned in the space formed between the standard and the burner, and a generator member positioned above the burner and connected to the valve and having means for connection with a source of fuel supply.

30 4. A gas generator and burner, comprising a support, a supply member connected thereto and having an upstanding nozzle and a valve controlling the fuel supply thereto, a standard connected to the supply member and having a bore entered by the nozzle and also having an air inlet opening, a burner member carried by the standard and having upwardly extending tubular burner projections and a burner opening and an opening in communication with the air inlet opening, an upper casing positioned above the burner member and having spaced openings into which the projections extend, a casing engaging the standard and the burner for directing vapor from the standard to the burner opening, a perforated conduction member positioned in the space formed between the standard and the burner and through which conductor the vapor passes, and a generator member positioned above the burner and connected to the valve and having means for connection with a source of fuel supply.

55 5. A gas generator and burner, comprising a support, a supply member connected thereto and having an upstanding nozzle and a valve controlling the fuel supply thereto, a standard connected to the supply member and having a bore entered by the nozzle and also having air inlet openings, said standard also having radial ports which extend from the bore outwardly, a burner member surrounding the standard and having an opening in communication with the air inlet openings for directing air around the burner

openings, a casing engaging the standard and the burner and forming a mixing chamber for directing vapor from the standard to the burner openings, a perforated conduction member positioned in the space formed between the standard and the burner and through which conductor the vapor passes, and a generator member positioned above the burner and connected to the valve and having means for connection with a source of fuel supply.

6. A gas generator and burner, comprising a support, a supply member connected thereto and having an upstanding nozzle and a valve controlling the fuel supply thereto, a standard connected to the supply member and having a bore entered by the nozzle and also having air inlet openings, said standard also having radial ports which extend from the bore outwardly, a burner member surrounding the standard and having an opening in communication with the air inlet openings for directing air around the burner openings, an upper casing mounted on the burner in spaced relation to form a continuation of the air directing means and having openings in register with the burner openings, a casing engaging the standard and the burner and forming a mixing chamber for directing vapor from the standard to the burner openings, a perforated conduction member positioned in the space formed between the standard and the burner and through which conductor the vapor passes, and a generator member positioned above the burner and connected to the valve and having means for connection with a source of fuel supply.

7. A gas generator and burner, comprising a support, a supply member connected thereto and having an upstanding nozzle and a valve controlling the fuel supply thereto, a standard connected to the supply member and having a bore entered by the nozzle and also having air inlet openings, said standard also having radial ports which extend from the bore outwardly, a burner member surrounding the standard and having upwardly extending burner projections having burner openings, said burner member also having an opening in communication with the air inlet openings for directing air around the burner openings, an upper casing mounted on the burner in spaced relation to form a continuation of the air directing means and having openings in register with the burner openings, said standard and burner being formed of non-metallic material, a casing engaging the standard and the burner and forming a mixing chamber for directing vapor from the standard to the burner openings, a perforated conduction member positioned in the space formed between the standard and the burner and through which conductor the

vapor passes, and a generator member positioned above the burner and connected to the valve and having means for connection with a source of fuel supply.

- 5 8. A gas generator and burner, comprising a support, a supply member connected thereto and having an upstanding nozzle and a valve controlling the fuel supply thereto, a standard connected to the supply member and having a bore entered by the nozzle and also having air inlet openings, said standard also having radial ports which extend from the bore outwardly, a burner member surrounding the standard and having openings in communication with the air inlet openings for directing air around the burner openings, an upper casing mounted on the burner in spaced relation to form a continuation of the air directing means and having openings in register with the burner openings, a casing engaging the standard and the burner and forming a mixing chamber for directing vapor from the standard to the burner openings, a perforated conduction member positioned in the space formed between the standard and the burner and through which conductor the vapor passes, and a generator member positioned above the burner and connected to the valve and having means for connection with a source of fuel supply, said upper casing having upwardly extending flanges forming a means for holding liquid fuel for preliminarily heating the generator.
- 15 9. A gas generator and burner, comprising a support, a supply member connected thereto and having an upstanding nozzle and a valve controlling the fuel supply thereto, said supply member also having a valve controlled air inlet, a standard connected to the supply member and having a Venturi shaped bore into which the nozzle extends and the air inlet opens, said standard also having vertically extending air inlet openings and radial ports extending from the bore outwardly, a burner member surrounding the standard and having openings in communication with the air inlet openings and upstanding burner portions with openings, an upper casing mounted on the burner

in spaced relation and having open upwardly extending tubular portions which surround the burner portions for directing air therearound, a lower casing engaging the standard and the burner and forming a mixing chamber for directing vapor from the radial ports to the burner openings, a perforated conduction member positioned in the space formed between the standard and the burner and through which conductor the vapor passes, and a generator member positioned above the burner and connected to the valve and having means for connection with a source of fuel supply.

10 10. A gas generator and burner, comprising a support, a supply member connected thereto and having an upstanding nozzle, and a valve controlling the fuel supply thereto, said supply member also having a valve controlled air inlet, means controlling both valves simultaneously, a standard connected to the supply member and having a Venturi shaped bore into which the nozzle extends and the air inlet opens, said standard also having vertically extending air inlet openings and radial ports extending from the bore outwardly, a burner member surrounding the standard and having openings in communication with the air inlet openings and upstanding burner portions with openings, an upper casing mounted on the burner in spaced relation and having open upwardly extending tubular portions which surround the burner portions for directing air therearound, a lower casing engaging the standard and the burner and forming a mixing chamber for directing vapor from the radial ports to the burner openings, a perforated conduction member positioned in the space formed between the standard and the burner and through which conductor the vapor passes, and a generator member positioned above the burner and connected to the valve and having means for connection with a source of fuel supply.

In testimony whereof, I affix my signature.

ARTHUR WHITE.
